UNITED STATES PATENT OFFICE.

CLAYTON E. WYRICK, OF DETROIT, MICHIGAN.

AUTOGRAPHIC REGISTER.

1,413,647.

Specification of Letters Patent. Patented Apr. 25, 1922.

Application filed August 21, 1920. Serial No. 405,153.

To all whom it may concern:

Be it known that I, CLAYTON E. WYRICK, a citizen of the United States, residing at Detroit, county of Wayne, State of Michigan, have invented a certain new and useful Improvement in Autographic Registers, and declare the following to be a full, clear, and exact description of the same, such as will enable others skilled in the art to which it pertains to make and use the same, reference being had to the accompanying drawings, which form a part of this specification.

This invention relates to self printing autographic registers and the object of the invention is to provide an autographic register in which a series of strips of paper are printed from a series of type rolls and maintained in registration. A further object of the invention is to provide an autographic register in which several strips of paper are printed simultaneously from different type rolls, the printing on the said strips being automatically brought into registration on a writing plate. Another object of the invention is to provide an autographic register in which slack might occur in the strips of paper between the printing rolls and writing plate, due to differences in the diameter of the printing rolls, is automatically taken up at the end of each rotation of each printing roll. A novel feature of the invention is that printing rolls of slightly different diameters may be used in this machine and the printing thereon will be automatically brought to registration so that it is not necessary to utilize carefully machined printing rolls to maintain the printing on the sheets in registration. These objects and the several novel features of the invention are hereinafter more fully described and claimed and the preferred form of construction by which these objects are attained is shown in the accompanying drawings in which—

Fig. 1 is a view of the machine with the side plate removed.

Fig. 2 is a section taken on line 2—2 of Fig. 1.

Fig. 3 is a section taken on line 3—3 of Fig. 1.

Fig. 4 is a perspective view of one of the printing rolls.

As shown in Figs. 1 and 3 a casing 1 is provided having an opening 2 on each side. The register is preferably provided with a

wooden base 3 secured to the metal base 4 of the register. Mounted on the base 4 is a series of standards 5 on each side of the paper rolls 6 which are provided with central shafts 7 rotatably mounted on the angular faces 8 of the standards 5. Each standard 5 is also provided with a slot 9 to receive the shaft 10 of the contact roller 11. A strip of paper 12 from each roll is passed about the respective roller 11 and is brought into contact with the printing face 13 of the printing rollers 14. At the bottom end of each slot 9 is a lug 15 which is provided with a threaded aperture for the screw 16, the screw 16 limiting downward movement of the roller 11. About the shaft 10 of the roller 11 is a spring 17, the lower end of which is inserted in an aperture provided therefor in the lower end of the screw 18 which is threaded through a lug 19 on the standard 5. This spring places a tension on the roller 11 and holds the paper about the roll 11 in contact with the type 13 and the screw 18 may be adjusted in the lug 19 to increase or decrease the tension of the spring 17. Each standard 5 is also provided with a slot 20 in which is positioned the shaft 21 of the printing roller 14, a screw 22 being provided to maintain the shaft 21 in position in the slot 20. The type on each roller 14 is preferably metal or it may be formed of a molded sheet rubber with the type formed thereon and the molded sheet is glued or tacked to the roll to secure the same thereon, as shown in Fig. 4. Each printing roll is provided with a gear 23 on the end thereof shown more particularly in Fig. 2 and between each pair of gears 23 is an idler gear 24 in mesh therewith so that should any one of the strips of paper 12 be withdrawn from the register the entire series of printing rolls will be rotated thereby. To ink each printing roll I provide an ink roll 25 which is rotatably mounted in arms 26 secured to a shaft 27 pivotally mounted in the lower end of the standards 5, as shown in Figs. 1 and 3. A flat spring 28 is also provided which is secured in the base 4 and holds the inking roll 25 in contact with the type so that the type is inked as it passes the inking roll. As shown in Fig. 4, the type does not completely cover the roll 14, there being a space 29 on the roll between the ends of the type which leaves a space between the printed forms. This portion 29 of the roll is flattened or

recessed as shown in Figs. 1 and 4 for a purpose hereinafter described. As shown more particularly in Fig. 3, a channel member 30 is secured to the side of the frame 1 by screws 31, the channel 30 having a vertically extending portion 32 which is notched at several points 33 to receive the shafts of the rollers 34. The vertical portion 32 is provided with an upwardly extending portion 35 at the end thereof which is also notched to receive the shaft ends of the rollers 36. A channel 37 is also provided which is secured to the opposite side of the frame 1 by screws 38, the channel 37 being 10 also provided with a vertically extending portion 39, similar to the portion 32 of the channel 30 which is similarly notched to receive the opposite ends of the shafts of the rolls 34, the portion 39 being provided with an upwardly extending portion at the end thereof similar to the portion 35 of the channel 30 which is also notched to receive the opposite shaft ends of the rollers 36. In this manner the rollers 34 and 36 are rotatably mounted in the upper portion of the casing. The strips of paper from the rollers 6 are passed about the contact roller 11 and rollers 34 and 36 as shown in Fig. 1, the strips being brought forward over the writing plate 40, as shown in Figs. 1 and 3. This writing plate 40, as shown in Fig. 3, is provided with an internal flange 41 on each side so that the plate 40 is positioned on the upright portions 32 and 39 of the channel members 30 and 37, the flanges 41 holding the plate 40 in position thereon as shown in Fig. 3. The channel 37 is made of sufficient width to receive a roll of carbon paper 42 which is preferably formed of two sheets of carbon paper 43 and 44 rolled together. 20 However, should more than three strips be printed it will be necessary to increase the number of carbon sheets to allow the required number of carbon copies to be made by writing on the strips. These sheets of carbon paper extend crosswise of the register and between the printed sheets 12 the sheets extending over the edge 45 of the casing 1 and outward therefrom. Over the writing table 40 is a top member 46 which is provided with flanges 47 engaging over the upper end of the frame members 1 and the member 46 is provided with an opening 48 therein over the writing plate 40 so that the operator may write on the top sheet 12 and a copy will be produced through the carbon paper onto the lower sheets 12. It will be noted that, when the cover is placed on the casing the ends of the carbon sheets extend downwardly beneath the flange 47 so that when the carbon paper becomes worn the top 46 may be lifted and the carbon sheets pulled through until fresh carbon is positioned between the 30 sheets 12 at which time the cover may be replaced and the sheets torn off against the edge 49 of the flange 47. To feed the sheets from the register preferably I provide a roller 50 which is provided with a crank 51 shown more particularly in Figs. 1 and 2, 70 the roller 50 being positioned beneath and in contact with the paper strips 12. Mounted on the cover 46 is a casing 52 containing a roller 53 which engages the sheets 12 on the upper side and the rollers 50 and 53 are 75 preferably geared together so that rotation of the roller 50 by the crank 51 also rotates the roll 53 and feeds the sheets 12 from the register through the slot 54 in the end of the casing 1. After the machine has been 80 threaded with the paper strips 12 as described and shown in Fig. 1, the crank 51 is rotated which pulls the strips 12 from the rolls 6 about the contact rollers 11 into contact with the type rolls 14, the type rolls 85 being geared together are each rotated simultaneously which prints the paper strips 12. If one of the type rollers 14 is very slightly greater in diameter than the remaining type rolls the printed paper from 90 the said roll will feed therefrom a little faster than the paper from the remaining rolls due to the printing rolls being geared together so that the strip 12 becomes slack between the contact roller 11 and respective 95 roller 34. To overcome this, the flat or recessed portion 29 is provided on each roll 14 and for the purpose of explanation we will presume that the paper from the central roll 6 shown in Fig. 1 becomes slack as 100 indicated by dotted lines 55 in Fig. 1. Under this condition the outward movement of the end strips 12 by rotation of the handle 51 rotates the type rollers 14 and through the idler gears 24 rotates the central type 105 roller 14. It can thus be seen that the rotation of the type rollers is accomplished through the end strips 12, the central strip 12 remaining slack and not aiding in the operation of the device, the central type 110 roller 14 being only operated by the end type rollers through the gears 24. As the central strip of paper 12 is printed from the respective type roll 14 the flat or recessed portion 29 thereof is moved to position beneath the roller 11 at the end of the printed form at which time the roller 11 is prevented from engaging the type roll by dropping onto the end of the adjustable screw 16 by action of the spring 17. As the 115 portion 29 is passing beneath the roll 11, the roll 11 is not rotated and thus the feeding of the central strip 12 is stopped until by the forward movement of the outer strips 12 the central strip is again pulled tight 120 between the central rollers 11 and 34. It will thus be noted that the spaces between the printed forms on the central strips are made smaller to agree with the smaller spaces between the printed forms on the 125 130

end strips 12. As the type plates are molded from the same form they are all of the same size and should the central printing roller be larger in diameter than the end printing 5 rollers the space or recessed portion 29 between the ends of the type will be greater in the central printing roller than in the end printing rollers. It is this space which is adjusted to the size of that of the smaller 10 printing rollers which causes the printing on the strips to all come in registration on the writing plate 40. The roller 14 being driven by the gears 24 is continued in rotation and the central strip 12 is again printed as the 15 flat portion 29 is moved from beneath the roller 11. In this manner any inequalities in the feeding of the different strips 12 from the type rollers is taken up so that when once set in operation the strips 12 will all 20 be delivered equally with the printing thereon in registration. If two of the strips become slack the device will be operated by the remaining strip which is taut and operates all the printing rolls through the idler 25 gears the slack in the two strips being taken up as the respective flat or recessed portion 29 thereof passes beneath the respective roller 11. Two of the portions 29 may be positioned beneath the respective rollers 11 30 at the same time under which condition the type rolls will be rotated by the remaining strip 12. With this condition the type roller for the remaining strip 12 need not be provided with a flat or recessed portion 29 as 35 under the condition the remaining strip 12 from the non-recessed roller continuously operates the recessed rollers and any inequalities which might occur in feeding are taken up by the recessed rollers as long as 40 the portions 29 thereof pass beneath the rollers 11 simultaneously. Under ordinary conditions, however, only one of the flat portions 29 will be positioned beneath the roller 11 at one time so that the slack in each strip 45 is taken up at different intervals the roller for the slack strip remaining stationary so that no paper is fed therefrom until the slack strip has pulled taut by movement of the strips by rotation of the handle 51. One 50 of the novel features of the invention is involved in the means of supporting the paper roll 6 within the register. As will be seen from Fig. 1, the shaft 7 of the roll 6 is positioned on the angular face 8 of the member 5, the outer periphery of the roll resting against and being supported on the roll 11 which is stationarily positioned adjacent the end of the adjusting screw 16. By this 55 means as the paper is unwound from the roll and the roll becomes smaller in diameter the shaft 7 moves down the angular face 8 by gravity so that the outer periphery of the roll is always in contact with the roll 11. It will be noted by the construction shown, 60 as the paper strips are unwound from the roll, the roll moves down the angular face 8 and continuously contacts the roll 11 and as this movement occurs the paper roll is continuously made smaller in diameter so that contact between the upper face of the 65 adjacent printing roll and paper roll can never occur. To allow adjustment of the slips to registration when the device is assembled the idler gear 24, as shown in Fig. 3, is rotatably mounted on a stub shaft 56 70 which is secured in the member 5. A space 57 is provided between the member 5 and adjacent wall 1 of the casing in which the gears 23 and 24 are rotatable. A cotter pin 58 extends through the end of the shaft 56 75 to retain the gear 24 in position. To bring the strips to registration when the machine is first assembled it is necessary to remove the pins 58 from the shaft 56 and move both idler gears 24 out of engagement with the 80 type roll gears 23, at which time the different units may be so timed as to bring the printing on the strips to registration. When this has been done the idler gears 24 are again moved into mesh with the type 85 roll gears and the pins 58 replaced. To allow a very slight adjustment for registration a screw 59 is provided which binds the gear 23 to the type roll shaft 21. By loosening this screw 59 the type roll may be slightly 90 rotated without changing the relationship of the gears. Once the machine is set at the factory so that the printing on the strips comes in registration it is not necessary to change the same as the type rolls are geared 95 together and the paper cannot be fed therefrom to the writing plate out of registration. This particular feature is very useful when 100 new rolls of paper are inserted in the register as it is not necessary to adjust any part of the machine to bring the printing on the strips in registration. It will also be noted that the operating parts of the machine are made up in units consisting of two brackets 105 5, a paper supply roll 6, a contact roll 11, a 110 type roll 14 and gear 23 therefor and an ink roll 25. Each unit is geared to the next succeeding unit by the idler gear 24 and as many units may be added to the machine as to produce the required number of printed 115 copies. In this case it is necessary to form the carbon roll of as many sheets as necessary to produce the required number of carbon copies or blank rolls may be added to the machine to make carbon copies of the 120 writing only in addition to the printed strips.

From the foregoing description it becomes evident that the device is very simple and efficient in operation, will automatically prevent the printed strips from becoming slack or out of registration and provides a device 125 which accomplishes the objects desired.

Having thus fully described my invention, what I claim and desire to secure by Letters Patent of the United States is—

1. In an autographic register the combination with a casing and a writing plate, of a series of paper rolls therein, a printing roller for each paper roll riding in contact with the paper strips therethrough and rotatable by the withdrawal of paper from the roll, the several printing rolls being geared to rotate in unison, each printing roll having a portion of the surface thereof shaped to release the paper strip from engagement with the respective printing roll, the printing rolls being positioned with the said shaped portions so that but one paper strip is released at any one interval.
2. In an autographic register, a series of paper rolls, a printing roll for each paper roll and rotatable by withdrawal of paper from each roll, each printing roll having a non-contact portion permitting movement of the respective strip of the paper roll without actuation of the printing roll, the printing rolls being geared to rotate in unison and so relatively positioned that all non-contact portions of the printing rolls are not brought to registration at the same interval.
3. In an autographic register, a plurality of paper rolls, a printing roll for the strip from each roll riding in contact therewith whereby the printing rolls are rotated upon withdrawal of the strips, means whereby the several printing rolls are caused to rotate through rotation of any one printing roll, each printing roll having a non-contact portion, the non-contact portions of the several printing rolls registering successively with the respective strips, a writing plate across which the strips are drawn from the paper rolls, and means for simultaneously withdrawing the several strips.
4. In an autographic register, a plurality of paper rolls, a printing roll for each paper roll, a contact roll between the printing roll and paper roll about which the strip from the paper roll is passed in contact with the printing roll, means whereby withdrawal of one of the strips from the paper rolls rotates the series of printing rolls in unison, and means for bringing each printing roll out of contact with the respective paper strip at predetermined intervals.
5. In an autographic register, a series of paper rolls, a series of printing rolls, a contact roll for each printing roll and its paper roll about which the paper strip from the paper roll is passed, yieldable means for holding the contact roll and printing roll in contact to print the paper strip therebetween, and means for bringing the printing roll out of contact with the paper strip at predetermined intervals.
6. In an autographic register, a series of

units each consisting of a paper roll, a contact roll in engagement with the surface of the paper roll and about which the strip of paper from the paper roll is passed, a printing roll normally in contact with the paper strip on the contact roll, means for bringing the printing roll out of contact with the paper strip at predetermined intervals, means for connecting the printing rolls of each unit together so that rotation of one printing roll rotates the remaining printing rolls, means for rotating the printing rolls by withdrawal of one of the paper strips and a writing plate over which the paper strips are passed with the printing thereon in registration.

7. In an autographic register, a series of sound paper rolls rotatably mounted therein, a series of contact rolls supporting the paper rolls, the paper strips from the paper rolls being passed about the contact rolls, a series of printing rolls normally in contact with the paper strips on the contact rolls, the printing rolls being connected together to rotate in unison, means for rotating the printing rolls by withdrawal of one of the paper strips, and a writing plate on which the printing on the several strips is brought to registration.

8. In an autographic register, a pair of paper rolls, a printing roll for each paper roll, one of the printing rolls having a non-contact portion, the two printing rolls being geared together to rotate in unison, a writing plate across which the strips from the paper rolls may be drawn, means for simultaneously withdrawing the several strips, and a sheet of carbon paper between the said strips.

9. In an autographic register, a series of paper rolls, a series of printing rolls, a contact roll for each printing roll and paper roll about which the paper strip from the paper roll is passed, yieldable means for holding the contact roll in contact with the type on the printing roll whereby the paper strip is printed upon withdrawal thereof, a non-contact portion on the printing roll, and adjustable means preventing the contact roll from coming in contact with the non-contact portion of the printing roll.

10. In an autographic register, a series of paper rolls, a series of printing rolls, a series of contact rolls about which the strips from the paper rolls are passed, the contact rolls holding the strips in contact with the printing rolls, a gear on each printing roll shaft, an idler gear between each pair of printing roll gears in mesh therewith, a writing plate over which the paper strips may be drawn, means for disengaging the idler gears to allow adjustment of the printing rolls to bring the printing on the said strips in registration on the writing plate, and means for adjusting the printing roll gear in relation to the printing roll.

11. In an autographic register, a series of printing rolls of different diameters, a paper roll for each printing roll across which the strip from the paper roll may be drawn in printing contact, means for feeding the several strips across the respective printing roll to receive an impression therefrom, the several strips being placed in superimposed relation, and automatic means for maintaining the strips with the printed matter thereon substantially in registration.
- 5 In testimony whereof, I sign this specification.

CLAYTON E. WYRICK.
